UNITED STATES PATENT OFFICE.

GEORGE KRELL AND GUY M. MARTINET, OF SAPULPA, OKLAHOMA; SAID MARTINET
ASSIGNOR TO SAID KRELL.

CLAMP.

Application filed May 5, 1927. Serial No. 188,923.

Our invention relates to clamps of a type employed for letting in and removing tubing and casing to and from an oil well and commonly designated elevators or spiders, 5 the principal object of the invention being to facilitate application of the clamp to the tubing or casing, automatic application of the gripping jaws or slips to the tubing or casing and control of the jaws or slips for 10 facilitating release of the tubing or casing and return of the jaws or slips to normal relation with their carrier.

In accomplishing these objects we have provided improved details of structure, the 15 preferred forms of which are illustrated in the accompanying drawings wherein:

Fig. 1 is a perspective view of a clamp embodying our improvements, illustrated in functional relation to a joint of tubing and 20 hereinafter termed a tubing elevator without intent to limit the invention to such particular use.

Fig. 2 is a plan view of the elevator, parts being broken away for better illustration.

25 Fig. 3 is an enlarged detail perspective view of the elevator in open position.

Fig. 4 is an irregular vertical section on the line 4—4, Fig. 2.

30 Fig. 5 is a vertical section on the line 5—5, Fig. 2.

Fig. 6 is a detail perspective view of one of the frame members.

Fig. 7 is a detail perspective view of one of the slip carriers.

35 Fig. 8 is a detail view of one of the slips.

Fig. 9 is an enlarged vertical section of the hinge joint between the frame members.

Referring more in detail to the drawings: 1 and 2 designate the paired frame mem-

40 bers each comprising front and rear walls 3—4 and a floor 5, the floor being provided with an arcuate recess 6 to permit application of the frame members to the tubing. The rear walls 4 are provided with hinge barrels 7 receiving a pin 8 upon which the respective halves of the frame may swing to open and close the frame. The barrels 7 are backset from the rear walls 4 on arms 9 so that the free edges of the wall members

45 of respective frame members may abut in a vertical plane.

The front wall 3 of the frame member 2 is provided with forwardly directed ears 10 carrying a hinge pin 11 and hingedly mounted on said pin is a latch 12 comprising the

arms 13 and head 14 adapted to swing over and receive a vertical rib 15 at the edge of the front wall of the opposite frame member 1. The latch 12 is yieldingly urged to its functional position by a spring 16, having end coils surrounding the hinge pin 11 and anchored to the frame ears 10, and a central portion 17 extended forwardly and bearing against the front face of the latch head 14. The latch 12 carries a handle 18 member 19 and the frame member 1 a handle 19 for facilitating opening and closing movement of the frame members and manipulation of the latch.

The front and back walls of each of the 70 frame members are recessed about midway of their height to provide trunnion sockets 20 which open through the edges of the walls and are adapted for closure to retain the slip carrier trunnions, presently described, 75 by blocks 21 that are held in place by pins or bolts 22 extending through vertical apertures 23 in the portions of the side walls above and below the trunnion sockets.

The slip carriers 24—25 comprise semi-flask-like members, each comprising a downwardly tapered concave seat 26 co-operative with a similar seat on the mating carrier to form a downwardly tapering bore for a set of jaws or slips, the seat 26 terminating in an inset shoulder 27 forming a stop for the slips and the lower edge of the carrier being tapered upwardly to the edge of the shoulder to facilitate downward application of the clamp over a joint of tubing.

90 Each of the carriers 24—25 is intended for carrying a plurality of slips, preferably two, as illustrated in the present drawings, and to key the slips in the carrier for longitudinal opening and closing movement and for lateral pivotal movement for adjustment on a tube, we provide the carriers with vertical grooves 28, each extending from near the top of the carrier to slightly beyond and through the shoulder 27, forming sockets 29 for seating the springs 30 which serve to restrain the slips in open position and to return the slips to open position after release of the slips from a tube.

Extending through the upper and lower 105 edge portions of the carrier into the upper and lower portions of the grooves 28 are bores 31 through which the anchoring pins 32 are passed, the pins having heads 33 at their lower ends seated within countersunk 110

recesses 34 in the lower edges of the carrier and having nuts 35 at their upper ends seated on beveled bosses 36 on the upper edges of the carriers to accommodate the pin to 5 the tapered angle of the slip seat and anchor groove.

Each of the slips comprises a substantially quarter-round block 37 having a concave inner face 38 provided with upwardly directed teeth 39 and having a tapered outer face and side edges to permit the assembled slips to seat within the tapered bore of the carrier. On the outer face of each of the slips 37 is an ear 40 adapted for sliding fit in a 15 vertical groove 28 in a slip carrier and having a vertical aperture 41 of sufficiently greater diameter than that of the anchor pin 32 to permit the ear to slide readily over the pin when the parts are assembled. On 20 the upper end of each of the slips is a finger 42 having a concave inner face 43 adapted for free movement over the outer wall of a tube and a flat upper face 44 adapted for engagement with the lower edge of a collar 25 45 of a tube 46 to interrupt travel of the slip and effect closing of the clamp about the tube as will presently be described.

The clamp is adapted for two opening and closing movements—one a hinged movement of the halves of the frame on the vertical hinge previously described, and the other a swinging movement of the slip carriers on transverse axes to permit the slips to swing toward and from the tubing to 35 effect a gripping relation of the slips on the tubing or release therefrom. The swinging of the slips and their carriers is on the trunnions 47 projecting from the front and rear inner corners of the carriers and seating in 40 the sockets 20 in the front and rear walls of the frame members 1 and 2, the trunnions being located below and inwardly of the centers of gravity of the carriers, so that when unrestrained, the carriers will swing 45 rearwardly to space the upper portions thereof away from the tubing to which the clamp is applied, the extent of swinging movement of the carriers being limited by contact of their outer edges with the end 50 walls of the frame members.

The clamp is suspended from bail members 49 hung in the derrick in any usual manner and seated in transverse sockets 50 in arms 51 extending from the upper portions of the slip carriers, the bails having free pivotal movement in the sockets to axially support the carriers and held in place by keeper blocks 52 bolted to the arms 51 and covering the outer ends of the sockets 60 to prevent escape of the bails, without limiting their axial movement.

Assuming that a clamp constructed and assembled as described is to be used for pulling tubing from a well, the operation is 65 as follows:

The upper joint of tubing having been left suspended on a spider with its coupling collar a substantial distance above the spider, the clamp is applied to the tubing by unlatching the frame members, swinging 70 them outwardly on their vertical hinge, bringing the clamp members about the tubing and then closing the clamp members to locate the tubing within the slips.

When the clamp is located about the tubing it may rest on the spider and weight of the slip carriers and of the suspending bails will tend to spread the carriers on their swinging mounting and thereby provide an adequate opening for receiving the tubing so 75 that the clamp may be applied thereto. After the clamp has been applied to the tubing and latched, the bails are lifted, initial lifting movement tending to close the carriers over the tubing and continued lifting movement carrying the slips along the tubing until the fingers 42 reach and engage the coupling collar on the upper end of the tubing (Fig. 1). When this engagement 80 takes place, the slips are held and their carriers moved upwardly along their tapered faces, compressing the springs 30 and forcing the slips inwardly to gripping relation with the tubing. When this gripping relation is effected, the slips resume their lifting movement with the clamp and carry the tubing with them because of the engagement of the upper edges of the slip fingers with the lower edge of the coupling collar, and also 85 because of a gripping relation of the slip teeth with the body of the tubing below the coupling collar; it being apparent that because of the secondary grip of the slips on the tubing, tendency of the collar to strip from the tubing under weight of the string 90 of tubing supported therefrom is obviated; lift from the collar being supplemental to lift from the slip connection and serving to insure retention of the tubing in case the slip teeth should fail to hold the weight of 95 the tubing.

When the joint of tubing has been elevated through the spider to a point where the collar of a succeeding joint is exposed, 100 the upper joint is unscrewed and carried to one side of the platform. When the joint of tubing is let down onto the platform and the clamp relieved from its weight, weight of the slip carriers, supplemented by weight 105 of the bails, tends to spread the carriers away from the tubing, drawing the slips with them to remove the slips from gripping contact with the tubing. When the slips have been removed from their gripping contact with the tubing, the springs 30 shift the slips outwardly in their carriers, tending 110 to open the slips ready for application to another joint of tubing.

It is apparent from the foregoing that we have provided a clamp of this character 115

which may be easily and quickly applied to tubing or casing, which is semi-automatic in its operation in that it will open under its own weight and under tension of the slip spreading springs to prevent freezing of the slips in their carriers.

It is further apparent that because of the tapered mounting of the slips in their carrier, there will be a reaction of the slips under load, but that such reaction is offset by the leverage exerted on the carrier from the bail mounting on the carrier arm operating on the fulcrum provided by the trunnions whereby the carrier is pivotally mounted on its frame.

What we claim and desire to secure by Letters Patent is:

1. A clamp of the character described comprising frame members, carriers swingingly mounted in the frame members on horizontal axes, located below and inward of their centers of gravity and having tapered seats, slips keyed to the carriers for longitudinal movement in said seats, and means supporting the clamp from the carriers.

2. A clamp of the character described comprising hingedly connected frame members having side and end walls, carriers pivotally mounted between the side walls and adapted for stop engagement with the end walls of respective frame members, tapered slips keyed to the carriers, means yieldingly restraining the slips, and means connected with the carriers for suspending the clamp.

3. In a clamp of the character described, hingedly connected frame members comprising spaced walls having paired trunnion bearings, carriers having trunnions seated in said bearings and having tapered seats, tapered slips keyed to the carriers for longitudinal movement in said seats, and means suspending the clamp from the carriers.

4. In a clamp of the character described, frame members, carriers pivotally mounted in the frame members, comprising tapered seats having stop shoulders at their lower ends, tapered slips keyed to the carriers for vertical movement in said seats and limiting engagement with said shoulders, and means connected with the carriers for suspending the clamp.

5. In a clamp of the character described, frame members, carriers pivotally mounted in the frame members, comprising tapered seats having vertical grooves in their side walls, pins extending through said grooves, tapered slips in said seats having ears projected into said grooves and pivotally anchored on said pins, and means connected with said carriers for suspending the clamp.

6. In a clamp of the character described, frame members, carriers pivotally mounted in the frame members, comprising tapered seats having vertical grooves in their side walls, pins extending through said grooves,

tapered slips in said seats having ears projected into said grooves and pivotally anchored on said pins, springs in said grooves engaging said ears to restrain the slips, and means connected with said carriers for suspending the clamp.

7. In a clamp of the character described, a frame, carriers swingingly mounted in said through the grooves, downwardly tapered seats having shoulders at their lower ends and having vertical grooves, pins extending through the grooves, downwardly tapered slips in said seats having ears extended into the grooves and pivoted on said pins to key the slips for vertical and pivotal movement in the carriers, springs seated in said grooves surrounding the pins and engaging said ears to restrain the slips, fingers on the upper ends of the slips for engaging a tubing collar, and means connected with said carriers for suspending the clamp.

8. In a clamp of the character described, hingedly connected frame members each comprising side walls and a back wall, a carrier swingingly mounted between the side walls of each frame member, on an axis forward of and below its center of gravity, and adapted for engaging the back wall to limit its opening movement, tapered slips keyed to the carriers and means connected with the carriers above and rearward of their centers of gravity for suspending the clamp.

9. In a clamp of the character described, hingedly connected frame members each comprising side walls and a back wall, a carrier having trunnions mounting on the side walls, slips having tapered seat in the carrier and hanger members pivotally supporting the carrier from points above and outwardly of the vertical planes of the trunnions to effect leverage of the slips against the object clamped thereby, to offset reaction imparted to the slips through their tapered mounting.

10. A clamp of the character described including carrier supporting means, paired carriers pivotally mounted on said means below and forwardly of their centers of gravity to swing apart when unrestrained, means suspending the carriers outwardly of their mountings to close the carriers under weight of the carriers, and slips in said carriers for gripping an object when the carriers are closed.

11. A clamp of the character described including carrier supporting means paired carriers pivotally mounted on said means below and forwardly of their centers of gravity to swing apart when unrestrained, means suspending the carriers outwardly of their mountings to close the carriers under weight of the carriers, yielding slip supporting means in the carriers, and tapered slips slideable in said carriers against the tension of said yielding means to grip an

object and automatically returnable by said means when the carriers are opened.

12. A clamp of the character described including carrier supporting means, paired carriers pivotally mounted on said supporting means eccentrically of their centers of gravity to swing apart when unrestrained, means suspending the carriers eccentrically

of their mountings and their centers of gravity to close the carriers under weight of the carriers and slips in said carriers for gripping an object when the carriers are closed.

In testimony whereof we affix our signatures.

GEORGE KRELL.
GUY M. MARTINET.
